United States Patent Office.

JAMES E. REQUA, OF SONORA, CALIFORNIA.

Letters Patent No. 100,068, dated February 22, 1870.

IMPROVEMENT IN THOROUGH-BRACES.

The Schedule referred to in these Letters Patent and making part of the same

To all whom it may concern:

Be it known that I, JAMES E. REQUA, of Sonora, in the county of Tuolumne, and State of California, have invented a new and improved Thorough-Brace; and I do hereby declare that the following is a full, clear, and exact description thereof, which will enable others skilled in the art to make and use the same, reference being had to the accompanying drawings forming part of this specification.

This invention relates to improvement in thorough-braces for carriages or other vehicles to which they are applicable; and

It consists in the thorough-brace constructed as hereinafter specified.

Figure 1 represents a longitudinal section of a part of a carriage-frame, with my improved braces applied to it; and

Figure 2 represents a plan view of the same.

Similar letters of reference indicate corresponding parts.

A represents my improved braces, which I propose to make of wire by braiding the same into flat thin strips, of any suitable dimensions, as required by the

case in hand, and joining the ends by swivel connections, B, and a right-and-left threaded screw.

I have found by experiment that by the employment of wire for these, braces instead of leather, much greater strength and durability may be had with the same weight of material. I propose to galvanize the wire, or protect it in other approved ways against corrosion, and I propose to use these braces in all application to carriages where leather braces are now used.

Having thus described my invention,
I claim as new and desire to secure by Letters Patent—

The thorough-brace, consisting of the flat belt A, formed of braided wires, and the connection B C, the swivel loops being made broad and straight at their outer ends to receive the ends of the belt, all constructed and arranged as shown and described.

The above specification of my invention signed by me this 4th day of September, 1869,

JAMES E. REQUA.
